CONSTITUTION AND MANUFACTURE OF
STUFFING AND PADDING PIECES FOR
GARMENTS OR THE LIKE

François Chassaing, Alfortville, France

Application April 21, 1937, Serial No. 138,246
In France April 27, 1936

2 Claims. (Cl. 223—57)

The present invention relates to constitution and manufacture of stuffing and padding pieces particularly shoulder-pieces for garments.

In fact such pieces are frequently used in 5 clothing making either to correct figure imperfections or, according to exigency of fashion, to increase the elegance of garments. Besides these stuffing and padding pieces avoid cavities which would rapidly put the vestment out of shape.

10 Thus these pieces are used for two purposes: to rectify the shape and to maintain it.

Mostly, tailors make up, according to requirements, shoulder-pieces and other stuffing pieces from sheets of cloth or cotton-wool or like material but this making-up is long and expensive.

15 Several standard shoulder-pieces of different sizes have been manufactured. Most of these shoulder-pieces comprise sheets of cloth and/or cotton-wool sewn together. They lack flexibility, elasticity and they sag rapidly; consequently their shape is spoiled and the garment comes out of form.

20 It has been proposed to make such stuffing and padding pieces by means of horse-hair united by a binding material, as rubber, and then to shape them.

25 The pieces made in that manner give better results than the first-mentioned ones but they present some drawbacks:

30 The seam of the shoulder-pieces on the garment makes a visible and unpleasant trace, and in the long run the stuffing-piece sags.

35 The hair-ends, which are not easily joined with the surface of shoulder-piece, get straight again, pass through the lining of the garment and they prick the wearer in an unpleasant manner.

40 It has been attempted to make up stuffing and padding pieces of sponge rubber, but their shaping is so difficult and so expensive that hitherto they could only be made flat. In that state they cannot suit the shape of the garment without altering the figure.

45 The present invention has for its purpose to obviate the aforesaid drawbacks and it provides to that end the constitution and manufacture of stuffing and padding pieces for clothes or the like, so as to obtain flexible, elastic, undefeatable and light pieces.

50 The stuffing and padding pieces in conformity with the invention comprise a core formed with entangled long and resisting fibres impregnated with a binding material such as glue, gelatine, resin, a solution, suspension or dispersion of rubber, latex, vulcanized latex and the like and this 55 core is entirely covered by a wrapper of cloth,

linen, felt, paper or other suitable material, the inner face of which preferably receives a coating which may be an adhesive substance.

In order to obtain such stuffing and padding pieces, fibres in a suitable quantity are put at 5 first in a preliminary form, and are impregnated with the binding material, either by immersion or by spraying and this mass is introduced in a preliminary mold, the shells of which are pressed together.

10 Preferably the engagement of both members of the mold takes place only at the edges of the stuffing piece to be made. Thus these edges are made thinner by the pressure exerted on both shells and the material in excess is cut off. Moreover the clipping out operation could be made by hand.

15 The sheet used as wrapper of the fibrous core is divided into two leaves of suitable size, i. e., corresponding respectively to the inner face and to 20 the outer face of the stuffing piece. It is however recommended that the size of the leaves be slightly larger than that of the faces of the fibrous bodies, so as to render possible a perfect pasting on the edges.

25 Both leaves are coated with adhesive material and shaped in mold of suitable configuration. The shaped leaves are put on the fibrous mass and the whole is introduced in the final mold which presses the edges and cuts off the excess of 30 material.

35 The compression is preferably exerted with action of heat on the whole surface of piece and consequently, not only the fibrous mass sticks to the wrapper and is protected against pressing, but the ends of fibres are fixed and cannot pierce the wrapper.

40 After a stay of suitable duration in the mold under pressure, the excess of material is cut off by hand at the edges and the piece is ready for use.

45 A modification of the operation would consist of enveloping by hand the fibrous mass in both leaves of the wrapper and compressing it as hereinbefore explained.

49 Agglomeration of the fibrous mass must be made so as to avoid any tendency of this mass to sink either under action of movements of the wearer or under action of the iron or ironing machine.

50 For this purpose it is recommended that the binding material be without any adhesive power not only at the ordinary temperature but also at the ironing temperature.

55 When a solution or a suspension or a disper-

sion of rubber is used, there are incorporated therein products causing a quick vulcanizing at low temperature.

It is feasible also to impregnate or to sprinkle the fibrous mass with anti-adhesive products.

The annexed drawing illustrates, by way of example, a form of the invention.

Fig. 1 shows a shoulder-piece in conformity with the invention, some parts being broken.

Fig. 2 shows a section of a mold arranged to make such a shoulder-piece.

Fig. 3 shows the same mold open.

It is seen on Fig. 1 that the shoulder-piece (as all stuffing or padding pieces in conformity with the invention) comprises a core 10 formed with agglomerated fibres and covered on its inner and outer faces with a wrapper 11 in fabric or other sheet material.

The core 10 and the wrapper 11 are at first made up so as to have the form of a shoulder-piece.

To obtain the final configuration it is recommended to use a mold of the type shown in Figs. 2 and 3, i. e., comprising two parts: a concave member 12 disposed on a base 13 and a convex member 14 attached to a lever 15 pivoted at 16 on the base 13.

The shell or concave member 12 of the mold lays on a movable plate 19 engaged in the base 13. In a chamber 20 under this plate, a fluid under pressure (air or water) may be introduced either directly or in a deformable bag, so as to raise the plate 19 and to bring the members 12 and 14 together.

The drawing shows the configuration of members 12 and 14. It is easy to remove these members and to change them for others, if the machine is to be used to make pieces of different shape.

The molding operation of a padding piece is made as follows:

The whole comprising the fibrous mass 10 and the two sheets 11 of the wrapper is, after a preliminary making-up, introduced in the shell 12 of the mold. The lever 15 is put down and its hook 17 engages the yoke 18. The plug 14 enters the shell 12 and is laid on the piece to be molded. Then the fluid under pressure is introduced into the chamber 20, so as to raise the shell 12 of the mold and to compress strongly the padding piece 10, 11.

It is recommended to fulfill this operation with intervention of heat.

As the raise of the shell 12 is made regularly any displacing or creasing is avoided.

The molding operation hereinbefore described might be made with plates bearing several molds which are tightened up simultaneously, but it would be, in that case, necessary to afford great care and attention, so as to avoid a turning up of fibres or a creasing of the wrapper. Therefore, it is preferable to use each mold separately; that permits a better control of the work and ensures obtention of thin and regular edges for the finished articles.

It is evident that the invention is not limited to the example hereinbefore described and comprises the execution of stuffing and padding pieces by other means.

I claim:

1. A method of fabricating a padding member adapted for use in clothing and embodying a fibrous body suitably shaped and covered with a casing, comprising coating two sheets of fabric, having surfaces slightly larger than those of the upper and lower faces of the fibrous body, with adhesive on the applicatory surface, contouring and bending said sheets by compression in a mold to a shape identical with that of the fibrous body, applying the coated face of each sheet to the corresponding portion of said fibrous body, and finally compressing the assembly in such a manner as to cause the two sheets to adhere to the fibrous body and to cause the joined edges of these sheets to adhere together along the periphery of the fibrous body.

2. A method for fabricating a padding member adapted for use in clothing and embodying a fibrous body, suitably shaped and covered with a casing, comprising coating two sheets of fabric, having surfaces slightly larger than those of the upper and lower faces of the fibrous body, with adhesive on the applicatory surface, contouring and bending said sheets by compression in a mold to a shape identical with that of the fibrous body, applying the coated face of each sheet to the corresponding portion of said fibrous body, and finally compressing and subjecting the assembly to the action of heat so as to cause the two sheets to adhere to the fibrous body and to unite the joined edges of these sheets together along the periphery of the fibrous body.

FRANCOIS CHASSAING.
